UNITED STATES PATENT OFFICE.

ABEL C. OSBORNE, OF EAST SAGINAW, MICHIGAN, ASSIGNOR TO A. EUGENE KIRBY, TRUSTEE, OF SAME PLACE.

BARBER'S APPLIANCE.

SPECIFICATION forming part of Letters Patent No. 427,241, dated May 6, 1890.

Application filed September 18, 1889. Serial No. 324,365. (No model.)

To all whom it may concern:

Be it known that I, ABEL C. OSBORNE, a citizen of the United States, residing at East Saginaw, in the county of Saginaw and State 5 of Michigan, have invented certain new and useful Improvements in Barbers' Appliances, of which the following is a specification:

The object of my invention is to provide a convenient receptacle for water to be used in 10 the toilet or by barbers for moistening the hand, brush, or cup, and which is adapted to be suspended or otherwise secured to a dressing-case, barber's chair, or like article of furniture within convenient reach of a person 15 making his toilet or of a barber in serving his customers; and my invention consists in a collapsible receiving-vessel having an aperture through which its contained air may be expelled by pressure upon the walls, and 20 through which aperture water will flow if the receiver in its collapsed condition be held in the water and allowed to resume its normal shape therein.

In the preferred form of my construction I 25 employ a hollow spherical body having its walls constructed of a flexible material, as rubber, so that they may collapse to expel the air, and a convenient means of suspension 30 consists of a textile covering, which may be made ornamental, if desired, and of such form as to inclose wholly or partially the spherical body, and having connected therewith a cord, hook, or other suitable fastening whereby to suspend or attach the receiver 35 from or to a piece of furniture or other support.

In the accompanying drawings, Figure 1 is a side elevation, and Fig. 2 a sectional elevation, of one form of my invention.

40 In said drawings, A represents a hollow spherical body whose walls are composed of rubber, and having therein an aperture a, through which the air may be expelled by collapsing the walls, and water drawn in 45 through said aperture by allowing said walls to expand while the aperture is immersed in water.

B indicates a netted covering intended to

illustrate a convenient method of suspending body A when filled with water from a chair 50 or other support. The cord C is connected therewith for a like purpose. I prefer the netted covering because it may be made ornamental, and because, also, it furnishes a secure hold when grasped by the hand; but it 55 is evident that instead of this netted covering a metal or other suspending or attaching means in the form of a hook, wire, rod, staple, or like device may be secured to, around, or through the walls of the body A in order to 60 attach it; or an integral handle of rubber may be cast with body A when the latter is made of rubber.

A use to which my invention is peculiarly adapted is that of conveniently supplying 65 water to a barber in his work. It is the custom among barbers, at one part of the operation of shaving a person, to moisten the hand or sponge before the face is gone over for the last time. It is inconvenient for a 70 barber to have near his chair a basin or other supply of water, and therefore he is either at the trouble of walking across the room while his customer waits or of using water from a bottle or other inconvenient receptacle. 75

The device which I have described, if filled with water and attached to the back of a barber's chair, supplies him with water for a 80 day's use, and all that is necessary to obtain it is to hold the hollow of the hand below the aperture a, and by gently pressing the walls of the body A water is expelled into the hand.

I do not limit my invention to the specific 85 form of construction illustrated in the drawings, as variations may be made within wide limits without departing from the spirit of my invention.

Having now described my invention, what 90 I claim as new, and desire to secure by Letters Patent, is—

1. As an attachment for barbers' chairs, a water-holder comprising, in combination, a collapsible receiver in hollow spherical form, 95 having an aperture through its wall, and suit-

able means for suspending or attaching said holder to an article of furniture, substantially as described.

2. As an attachment for barbers' chairs, a
5 water-holder comprising, in combination, a
collapsible receiver in hollow spherical form,
having an aperture through its wall, and a

netted covering and suspending-cord, substantially as described.

ABEL C. OSBORNE.
